UNITED STATES PATENT OFFICE.

JAMES C. DORR, OF DANSVILLE, NEW YORK.

SPEED-CHANGING MECHANISM.

1,115,058.

Specification of Letters Patent. Patented Oct. 27, 1914.

Application filed May 2, 1913. Serial No. 764,984.

To all whom it may concern:

Be it known that I, JAMES C. DORR, a citizen of the United States, residing at Dansville, in the county of Livingston and State 5 of New York, have invented a new and useful Improvement in Speed-Changing Mechanisms, of which the following is a specification.

This invention relates to frictional power 10 transmission devices and particularly to means for transmitting power from a driving member to a driven member which is capable of acting both as a clutch and as a speed changing mechanism.

15 The present invention is designed primarily for use as a transmission device for motor vehicles but it is obviously applicable to other uses. In accordance with the invention a pair of friction members or 20 disks are provided, one of which is connected with any suitable power device and will be termed the "driving disk", while the other is connected with the member to be driven and will be termed the "driven disk".

25 Power is transmitted through the engagement of the lateral faces of these disks whereby the shafts on which the disks are mounted may be placed in such approximate alinement as to permit the use of what 30 is known as shaft drive for the vehicle in place of chain drive, which has been required by many of the friction drives which have heretofore been proposed for motor vehicles.

35 The present invention provides a novel and peculiar configuration for the engaging faces of the friction disks whereby relative movement of the disks may be utilized to vary the speed of transmission and also to 40 reverse the direction of travel of the vehicle, the engaging faces being so shaped, however, that approximately true rolling contact is secured at all times, such contact invariably being line as distinguished from point 45 contact. By reason of the novel configuration of these surfaces, a wide range of relative movement and consequently of speed variation is possible, wear is minimized and frictional engagement adequate to drive the 50 vehicle under any and all conditions is assured.

In the accompanying drawings: Figure 1 is a side elevation of a motor vehicle chassis provided with a transmission mechanism embodying one form of the present invention, parts being shown in section and the outlines of the vehicle body being indicated in dotted lines. Fig. 2 is a section, on an enlarged scale, through the friction disks of the transmission mechanism showing the direct clutch-like engagement of the disks when their axes are alined, as when driving at high speed. Fig. 3 is a side elevation of a portion of the transmission mechanism, the driving disk being 60 shown in vertical section and the driven disk being shifted so as to be driven at a reduced speed. Fig. 4 is a vertical section through a part of the vehicle, showing the friction disks and their supporting devices 65 in side elevation. Fig. 5 is a vertical section through a part of the vehicle showing the friction disks in section and illustrating the position of the driven disk when the vehicle is to be driven backward. Fig. 6 is 70 a front elevation of the segment for locking the disk shifting lever. Fig. 7 is a plan view of a portion of the vehicle chassis and transmission mechanism. Fig. 8 is a similar view of a modified construction. Fig. 80 9 is a section on line IX-IX of Fig. 7. Fig. 10 is a detail view showing the shifting mechanism for the driving disk of the modified construction illustrated in Fig. 8. Fig. 11 is a diagrammatic view illustrating 85 the relative positions occupied by the friction disks in driving at different speeds and on reverse. Figs. 12, 13 and 14 are diagrammatic sectional views on lines XII-XII, XIII-XIII and XIV-XIV, respectively, of Fig. 11.

Having especial reference to Figs. 11 to 14, it will be seen that the transmission device of the present invention comprises essentially two friction members or disks 1 and 2, either of which may act as the driving member, although in the specific embodiment of the invention shown, 1 is the driving member and 2 the driven member. When the driven member is to be rotated 100 at the same speed as the driving member, the axes of the two members are in aline-

ment as shown in position *a* in Fig. 11, and Fig. 2, and the drive is direct just as though the disks were members of an ordinary friction clutch. The alined axes of rotation of the disks 1 and 2 is represented in Fig. 11 by the line *x*—*y*, and in the further consideration of the operation of the disks the axis of rotation of disk 1 is considered to remain stationary in this line. When the driven member is to be rotated at a different speed from the driving member, the axes of the disks are angularly displaced so as to bring a portion of the surface of one of the disks of large radius into contact with a portion of the surface of the other disk of less radius, as shown, for example, in Fig. 3 and in positions *b* and *c* in Fig. 11. By displacing the disks to such an extent that a portion of the surface at one side of the axis of one of the disks engages a portion of the surface of the other disk on the opposite side of the axis thereof, the two disks will be driven in opposite directions, thereby reversing the direction of movement of the driven disk. Such relative position of the disks is indicated in Fig. 5 and in positions *d* and *e* in Fig. 11.

The desired relative adjustment of the disks is preferably secured by mounting one of the disks, as shown, the disk 1, to rotate about a fixed axis, while the other disk rotates about a swinging axis. The two axes are brought into alinement when the driven disk is being rotated at the same speed as the driving disk, as already stated. In order to secure satisfactory engagement between the disks for all relative positions thereof as the axis of the disk 2 is swung out of alinement with the axis of the disk 1, the face 3 of disk 1 is concaved, as shown in Figs. 2, 3 and 11, by having an annular depression formed therein, the locus of the centers of curvature of the radical elements of which is a circle whose plane is perpendicular to the axis of disk 1 and passes through the center or centers about which disk 2 swings and whose radius equals the distance at which the center of swinging movement of the axis of the disk 2 is removed from the axis of rotation of the disk 1. The surface 3 of the disk 1 has a sort of cuspidal form rising to a point or cusp in the middle, as clearly shown in the drawings. Imagining a section to be taken through the disks in the plane in which the axis of the disk 2 swings, which is what is shown in Fig. 11, it will be seen that the contour of the surface of the disk 1 may be considered as described by two radii *f* and *g* swinging about centers *h* and *i* located at opposite sides of and at equal distances from the axis of rotation of the disk 1, extended, as indicated by the line *x*—*y*. The driving face of the disk 2 is divided into two annular surfaces 4 and 5, the contour of the surface 4 being de-

scribed by the radius *f* swinging about the center *h* whereby this portion of the disk surface will fit the surface of the disk 1 as the axis of the disk 2 swings about the center *h*. When the periphery of the disk 2 passes the axis *x*—*y*, so that the relative directions of rotation of the disks are reversed, the center about which the axis of the disk 2 is swung is changed from the point *h* to the point *i*, whereupon it will be seen that the portion 5 of the driving surface of the disk 2 engages and follows the surface of the disk 1, as shown in positions *d* and *e* in Fig. 11. The contour of the surface 5 is described by the radius *g* swinging about the center *i*, whereby it will be seen that the surface 5 fits the surface of the disk 1 as the axis of the disk 2 swings about the center *i*. At all times after the axes of the disks move out of alinement, a theoretical line contact is secured between the surface 3 of the disk 1 and either the surface 4 or the surface 5 of the disk 2. Owing to the shape of the surface 3 and to the fact that the axis of the disk 2 swings about a center at one side of the axis *x*—*y*, there will always be a clearance between the edges of the disk 2 and the disk 1, as indicated at 6 in Figs. 12, 13 and 14, so that substantial rolling contact is secured between the engaging portions of the surfaces of the disks at all times and sliding contact is reduced to a minimum.

It will be understood that the disks having surfaces of the configuration indicated and swinging about centers as specified, may be employed in any relation where it is desired to transmit power by means of friction gearing, and that either the disk 1 or the disk 2 may be used as the driving disk. The invention is, however, primarily intended for transmission devices for motor vehicles and the like and an embodiment of the invention in a motor vehicle will therefore now be described in detail.

As shown in Fig. 1, 10 is the frame of a motor vehicle chassis on which is mounted the motor 11 which drives the crank shaft 12. The disk 1 of the friction transmission mechanism is secured to the end of this shaft, while the disk 2 is mounted on the end of a shaft 13 which is operatively connected by means, such as a universal joint 14, to a shaft 15 which drives the rear wheels of the vehicle in any suitable manner, as through a differential gearing 16. A flexible shaft or other suitable device may obviously be substituted for the universal joint. The shaft 13 is supported in any suitable manner permitting it to swing, preferably by being journaled in a swinging frame 17 having a pivotal connection with the frame 10. In the preferred construction of the invention the side members of the frame 17 terminate in plates 18 having curved slots 136

- 19 and 20 therein, the latter of which is 19
preferably twice the length of the former. 20
Pins 21 and 22 pass through these slots and 25
form centers corresponding to the centers
5 *h* and *i*, indicated in Fig. 11, about which the
frame 17 carrying the shaft 13, successively
5 pivots. Fig. 4 shows the frame and shaft
in their lowest positions, the ends of the
slots 19 resting against the pins 21. As the
10 frame and shaft are swung upward so as to
shift the disk 2 relative to the disk 1 for
driving at slower speeds, the frame pivots
about the pins 21 as shown in Fig. 3. The
15 pins 21 continue to act as the axis of move-
ment for the frame until the portion of the
disk 2 engaging the disk 1 passes the axis
of rotation of the latter, at which time the
20 ends of the slots 20 engage the pins 22 as in-
dicated in Fig. 5. This engagement causes
25 the axis about which the frame swings to
shift from the pins 21 to the pins 22, this
new axis corresponding to the center *i* shown
in Fig. 11. It will thus be seen that further
25 swinging of the frame 17 and shaft 13 will
cause the portion 5 of the surface of the
disk 2 to engage and move in contact with
the surface of the disk 1. When the shaft
and frame are lowered, the reverse action
30 takes place.
- 30 The swinging movement of the frame,
shaft and disk may be controlled in any
suitable manner, as by means of a lever 23
having arms pivoted to the frame at 24 and
25 and projecting up to a position within
35 reach of the driver of the vehicle. Any
suitable means may be utilized for locking
the lever and frame in various positions,
the construction shown for this purpose con-
sisting of a segment 26 having a slot 27
40 therein through which the end of the lever
23 passes, this slot being provided in one
wall with a series of notches 28 adapted to
be engaged by a tooth 29 on the side of the
lever. The lever being pivoted to the frame
45 17 may be swung so as to move the tooth 29
into or out of the notches 28. A spring 30
is preferably provided for normally hold-
ing the tooth 29 in one of the notches. It
will be understood that any other locking
50 means may be utilized or that any other ar-
rangement for swinging the shaft of the disk
2 may be employed and that such shaft may
be swung downward or laterally instead of
upward if desired.
- 55 The engaging surfaces of the disks 1 and
2 may be formed of any suitable substances
between which there is a satisfactory co-
efficient of friction. For instance, one of the
disks may be of metal while the other is
60 faced with fiber. As shown, the disk 1 has
a metal bearing surface while the disk 2 has
secured to it a fiber ring 31 on which are
formed the annular surfaces 4 and 5. Means
are provided for holding the surfaces of the
- disks 1 and 2 in contact, these means prefer- 65
ably being of such nature that the disks may
be separated so as to disconnect the motor
from the driving wheels. In this way the
transmission disks may be made to take the
place of a clutch as well as of a speed chang- 70
ing device and thus perform the entire func-
tions of both clutch and transmission in the
ordinary motor vehicle, although it is to be
understood that a separate clutch may be
used in connection with the speed changing 75
disks if found desirable or necessary.
- The means shown in Figs. 1 to 7 and in
Fig. 9 for moving the disks into and out of
contact and for holding them in driving en- 80
gagement, comprise a pair of bars 35 which
carry the pins 21 and 22 and which are se-
cured to the frame of the vehicle in such
manner as to be capable of limited longitudi-
nal movement. As shown, the bars 35 are 85
supported adjacent to the pins 21 and 22
by means of pins 36 sliding in longitudinal
slots 37 formed in blocks 38 attached to the
frame of the vehicle. At their front ends
the bars 35 are pivoted by pivots 39 to lever
arms 40 fixed to a transverse shaft 41 jour- 90
naled in the frame 10. Also fixed to the
shaft 41 is a lever 42 provided with a foot
pedal 43 by which the shaft 41 may be
rocked and the bars 35 moved longitudi-
nally, as will be understood. The bars are 95
normally drawn forward, carrying with
them the frame 17, shaft 13 and disk 2, by
one or more strong springs 44 which thus
serve to hold the disk 2 in firm driving en- 100
gagement with the disk 1. A pair of these
springs 44 is preferably used, each spring
being secured at one end to a lug 45 on one
of the bars 35, and at the other end to a cross
member 46 of the vehicle frame. The disk 105
2 is held in driving engagement with the
disk 1 by these springs at all times except
when the disks are separated by pressure
upon the foot pedal 43. Any suitable lock-
ing means for this pedal may be utilized if 110
desired, so as to lock and retain the disks in
separated position. A pair of springs 47
may be provided if desired, engaging lugs 48
on the plates 18 of the frame 17 and being
anchored to any fixed part of the frame, 115
such as the cross bar 49. The springs 47,
which are weaker than the springs 44, serve
to partially or wholly balance the weight of
the frame 17, shaft 13 and disk 2 so as to
facilitate the shifting thereof. Where the 120
frame and disk are moved upward as illus-
trated, a suitable housing, such as indicated
at 50, may be provided to receive the same.
- Figs. 8 and 10 show a modified construc- 125
tion in which the pins 21 and 22, upon which
the frame 17 swings, instead of being car-
ried by movable bars 35, are mounted di-
rectly upon the frame of the vehicle. Thus
the frame 17, shaft 13 and disk 2 have a

swinging movement only, instead of both a swinging and longitudinal movement as in the embodiment of the invention above described. To provide for the proper frictional contact of the disks 1 and 2 and for the engagement and disengagement of the disks, the disk 1 is mounted in such way as to be axially movable toward and from the disk 2. As shown in these figures, the disk 1 is provided with a stem 55 from which projects a shaft 56 of square or other non-circular section which is slidably mounted in a tubular extension 57 of the main shaft 12 of the motor. The stem 55 of the disk 1 is slidably and rotatably mounted in a bearing 58 carried by the cross bar 46 of the vehicle frame. The disk 1 is urged toward the disk 2 by means of a spring 59, preferably surrounding the tubular member 57 and the shaft 56. In order to move the disk 1 away from the disk 2 so as to relieve the driving pressure between the two or entirely disengage the disks, any suitable device may be utilized. As shown, the stem 55 has a groove 60 formed therein in which fit the arms of a forked lever 61 secured to a transverse rock shaft 62. The latter is rocked by means of a lever 63 provided with a foot pedal 64 or otherwise.

From the foregoing description it will be seen that a transmission is provided which may be caused to act both as a clutch and as a speed changing mechanism. The construction of the device is, however, no more complicated than that of the ordinary friction clutch now commonly employed in motor vehicles, so that it will be seen that the invention accomplishes a saving in cost of construction equivalent to the entire cost of the speed changing mechanisms employed in most motor vehicles. The entire control of the transmission mechanism is accomplished by means of the lever and foot pedal shown. Perfect speed control is possible and at all speeds, both forward and reverse, a substantially perfect rolling line contact is secured between the disks which results in the transmission of adequate power with a minimum of wear and transmission loss. At the higher speeds, direct drive is provided for by the direct engagement of the two disks in the manner of a clutch, under which conditions there is no transmission loss and no wear whatever upon the disks.

I claim as my invention:

1. A speed changing mechanism including a pair of rotors having engaging lateral faces, one of said rotors being movable relatively to the other rotor, and means for moving said movable rotor about one center during a part of its movement and about another center during the other part of its movement.
2. A speed changing mechanism includ-

ing a pair of rotors having engaging lateral faces, one of said rotors being movable relatively to the other rotor, and means for swinging said movable rotor about a center located at one side of the axis of rotation thereof during a part of the movement of said rotor, and about a center located at the opposite side of the axis during the other part of the movement of said rotor.

3. A speed changing mechanism including a pair of rotors rotatable about axes capable of relative angular adjustment, said rotors having lateral faces engaging only along a common radial element when the axes of rotation of the rotors are out of alignment, one of said axes being adapted to swing about one center during a part of its angular adjustment and about another center during another part of its angular adjustment.

4. A speed changing mechanism including a pair of rotors having engaging lateral faces, one rotor having an annular concave face which has a central prominence, and means for swinging the other rotor about a point concentric with an element of said concave face extending radially of the rotor, into a plurality of positions in each of which said faces are in engagement.

5. A speed changing mechanism including a pair of rotors rotatable about axes capable of relative angular adjustment, said rotors having engaging lateral faces one of which is provided with an annular depression surrounding a central prominence, the face of the other rotor having an annular convex bearing surface fitting in said depression and means for swinging said rotor having the convex face about a point concentric with an element of said annular depression extending radially of the rotor.

6. A speed changing mechanism including a pair of rotors, one having an annular concave depression in a lateral face thereof surrounding a central prominence, the second rotor being mounted on a shaft arranged to swing about a center at one side of the axis thereof, said second rotor having a face adapted to engage the surface of the concave depression of the first rotor.

7. A speed changing mechanism including a pair of rotors rotatable about axes capable of relative angular adjustment, said rotors having engaging lateral faces, one of which is provided with two bearing surfaces adapted to engage the bearing surface of the other rotor, one of said surfaces being adapted to engage the other rotor at one side of the axial center thereof for driving in one direction, and the other surface being adapted to engage the other rotor at the other side of the axial center for driving in the opposite direction.

8. A speed changing mechanism includ-

ing a pair of rotors, one having an annular concave depression in a lateral face thereof surrounding a central prominence, the second rotor being mounted on a shaft arranged to swing about either of two centers located on opposite sides of the axis of said shaft, said second rotor having a pair of bearing surfaces adapted respectively to engage the bearing surface of the first rotor when the shaft of the second rotor is swung about one or the other of said centers.

9. A speed changing mechanism including a pair of rotors, one of which has an annular concave bearing surface, the radial elements of which are described by radii swinging about centers, the locus of which is a circle whose plane is perpendicular to the axis of rotation of said rotor, the second rotor having a lateral face adapted to engage the concave bearing surface of said first rotor, said second rotor being arranged to swing about a center lying in said locus circle.

10. A speed changing mechanism including a pair of rotors, one of which has an annular concave bearing surface, the radial elements of which are described by radii swinging about centers, the locus of which is a circle whose plane is perpendicular to the axis of rotation of said rotor, the second rotor having a lateral face provided with two convex bearing surfaces adapted to engage the concave bearing surface of said first rotor on opposite sides of the axis of rotation thereof, said second rotor being arranged to swing about one or the other of two centers lying at opposite ends of a diameter of said locus circle.

11. A speed changing mechanism including a pair of rotors having engaging lateral faces, one of said rotors being mounted to rotate about a fixed center, a shaft on which the other rotor is mounted, a movable frame in which said shaft is journaled, said frame being adapted to swing about one center during a part of the movement of said frame and about another center spaced at a distance from said first mentioned center during another part of the movement of said frame.

12. A speed changing mechanism including a pair of rotors, one of which has an annular concave depression in a lateral face thereof surrounding a central prominence, the second rotor being mounted on one end of a shaft, a frame in which said shaft is journaled, and a pair of pivotal supports for said frame located adjacent to the opposite end of the shaft and on opposite sides of and at equal distances from the axis of said shaft, said frame being adapted to swing alternately about said centers, said second rotor having bearing surfaces adapted to engage with the concave bearing surface of

said first rotor upon opposite sides of the axis thereof when said frame is swung about one or the other of said centers.

13. A speed changing mechanism including a rotor having an annular concave depression in a lateral face thereof surrounding a central prominence, a second rotor having a bearing surface adapted to engage the surface of the concave depression of the first rotor, a shaft on the end of which said second rotor is mounted, a frame in which said shaft is journaled, curved slots in the end of said frame remote from said second rotor, and pivot pins fitting in said slots, said pins adapted to act alternately as pivotal supports about which said frame may be swung.

14. A speed changing mechanism including a rotor having an annular concave depression in a lateral face thereof surrounding a central prominence, a second rotor having a bearing surface adapted to engage the surface of the concave depression of the first rotor, a shaft on the end of which said second rotor is mounted, a frame in which said shaft is journaled, curved slots in the end of said frame remote from said second rotor, pivot pins fitting in said slots, said pins adapted to act alternately as pivotal supports about which said frame may be swung, a movable member on which said pins are mounted, and means for moving said member in one direction or the other to cause the bearing surfaces of said rotors to be engaged or disengaged.

15. A speed changing mechanism including a rotor having an annular concave depression in a lateral face thereof surrounding a central prominence, a second rotor having a bearing surface adapted to engage the surface of the concave depression of the first rotor, a shaft on the end of which said second rotor is mounted, a frame in which said shaft is journaled, curved slots in the end of said frame remote from said second rotor, pivot pins fitting in said slots, said pins adapted to act alternately as pivotal supports about which said frame may be swung, a movable member on which said pins are mounted, a spring for moving said member in one direction, and a lever for moving said member in the opposite direction.

16. A speed changing mechanism including a pair of rotors having engaging lateral faces, a shaft upon the end of which one of said rotors is mounted, a frame in which said shaft is journaled and which is adapted to swing about an axis located at one side of the axis of rotation of said rotor, a movable member to which said frame is pivoted, and means for moving said member in one direction or the other to cause said faces of said rotors to be brought into driving engagement or to be separated.

17. A speed changing mechanism including a pair of rotors having engaging lateral faces, a shaft upon the end of which one of said rotors is mounted, a frame in which 5 said shaft is journaled and which is adapted to swing about an axis located at one side of the axis of rotation of said rotor, a movable member to which said frame is pivoted, a spring acting to move said member to hold 10 the faces of said rotors in driving engage-

ment, and means for moving said member against the force of said spring to separate said faces.

Witness my hand this 28th day of April, 1913.
